DETACHABLE BIT

Percill Liddicoat, Timmins, Ontario,
CanadaApplication February 16, 1935, Serial No. 6,894
In Canada February 17, 1934

9 Claims. (CL. 255—64)

In the present invention I have devised a detachable bit, adapted to be readily mounted on the shank of a rock cutting drill rod, which is so constructed that the successive blows which are received by the shank of the drill rod are transmitted to the sleeve or bit, in rock cutting, or similar uses of the invention. The detachable bit also readily locks itself on the shank of the drill rod by impacts received from the machine operating the drill rod. The locking action referred to is effected by the riveting and bending action of a plurality of lugs on the end of the drill rod hammering over the upper edge of the sleeve or bit to form a collar, or partial collar, on said sleeve or bit. This feature will be more fully described hereinafter.

In the present invention the impact, transmitted to the bit when the drill rod is operated, is taken practically over the blades of the bit, thereby tending to drill a straight hole into the rock or other material being drilled, as will be explained later.

The "torsion of rotation" of the bit when in operation is taken by the flat sides of the bit shank which fits into the sleeve recess, as will also be described later.

The type of bit under consideration also keeps centralized under all working conditions with the direction of the drill rod. The said bit can be easily and cheaply manufactured either by pressing, or drop forging without subsequent machining. The fact that the inner walls of the sleeve or bit are vertically parallel also facilitates the manufacturing operations in making the bit. This and other features of the invention will be described as the specification proceeds.

In the accompanying drawing, I have shown a physical embodiment of the present invention, constructed according to the best mode I have devised for same, in which:—

Figure 1 is a side elevation of the shank of a rock cutting drill rod with the detachable bit mounted thereon.

Figure 2 is a plan view of the bit, per se.

Figure 3 is a vertical section of the device, partly in elevation, taken on line 3—3, of Figure 2.

Figure 4 is a bottom view of the drill rod shown in Figure 3.

Figure 5 is a bottom view of the detachable bit shown in Figure 2.

In the drawing 1 indicates a rock cutting drill rod which is provided with a specially formed end 2 adapted to engage into the recess 3 formed in the detachable bit or sleeve 4. The sleeve 4 is preferably provided with a plurality of horizontally disposed cutting edges 5, 6, 7, 8 of the angular shape shown in Figures 1, 3 and 5 of the drawing. The recess 3 may be made either with a flat bottom 9, or a partially or fully concave

bottom 10, as desired. The said recess when first placed in contact with the bottom end of the drill rod, is provided with vertically parallel side walls 11, 12, etc. The bottom end 21 of the drill rod is formed to have a complementary shape to 5 the cross-sectional outline of the recess 3 of the bit, which in the drawing is octagonal in shape, but may be of cruciform, square, hexagonal, oval or any other similar cross-sectional outline. It will be noted that the bottom end 13 of the part 10 15 21 is slightly less in size than the size of the recess, so that the end of the drill rod may be easily inserted in the recess of the bit. The part 2 of the rod 1 is upset to form a plurality of lugs or enlargements 14, 15, 16 etc., each having a 15 recess 18 formed therein, as clearly shown in Figure 3 of the drawing. The purpose of these recesses is to provide a means of locking the bit 4 on to the shank 21 of the rod 1. It will be seen that the successive blows received by the rod 1 20 will tend to turn portions of the upper edge 19 of the bit 4 inwardly and thus lock the bit to the shank 21 of the drill rod, and yet when it is desired to remove the bit 4 this can be done by merely tapping the exterior surface of the bit 25 in several places with a hammer. It is found that by having the bottom of the recess 3 of the bit formed in a partially concave shape as indicated at 10 Figure 3 of the drawing, the 30 blows transmitted by the rod 1 to the bit are delivered on the outer circumference of the bottom end 13 of the shank, thus delivering circumferential impacts to the bit, which is found to be a working advantage in practice.

The passages 20 and 22, the former in the bit 35 and the latter passing through the drill rod 1 and the shank 21, are designed to permit water to flow through the rod and bit, and have direct play on the face of the rock being drilled, to wash away rock chippings, thus preventing rock dust 40 from injuring the operators of the device.

It will be noted that by having the bit readily detachable from the drill rod, said bit may be replaced by freshly sharpened bits frequently, as is necessary in tools of the kind under consideration.

The depth of the recess 3 in the bit is preferably made slightly greater than the length of the shank 21 on the rod as this permits the force of the blows from the rod at the commencement of 50 operation, to do the bending and riveting of the lugs or enlargements 15, 16 etc., over the top edge 19 of the bit, and thereby form a partial collar on the bit which locks the latter to the shank of the drill rod. After the attachment has been accomplished between the bit and the shank of the rod, the blows of the rod are delivered directly on the bottom 9 of the bit recess, which thereafter forms a seat for the bottom face of the shank and transmits the blows directly into the 60

material of the bit. The cross-sectional shape of the bit recess may be, as mentioned above, of varying shape to correspond with the cross-sectional shape of the shank of the drill rod depending on the users, or manufacturers requirements. The shank construction is of such a shape that it may be readily hand forged, machine forged, or made in a shaper or milling machine, and it can be made having a breaking strength equal to, or greater than, the main body of the drill rod. The shank is hardened and tempered after same is made into proper form.

The tempering of the bit is confined to the actual cutting faces 5, 6, 7, 8 of same, while the body portion of the bit is permitted to remain in a non-tempered state, in order to minimize wear on the lugs and shank of the drill rod.

It will be noted that due to the curved bottom 18 of the bottom of the recess 3 of the bit the impact from the drill rod is delivered on the circumference of the recess and delivered directly on the blades or teeth 5, 6, 7, 8, and this tends to drill a straight hole in the rock being drilled, and keeps the bit centralized with reference to the direction of impact of the drill rod.

It is evident that when the drill rod is operated there is a movement of rotation which is transferred to the bit and in order to accomplish this purpose the end of the rod shank and the vertical recess in the bit, are made of a shape such as hexagonal, octagonal, or oval etc., so that the torsion of rotation of the drill rod can be properly transmitted to the bit. Also as referred to in the preamble of this specification, the fact that the inner walls of the bit recess are vertically parallel facilitates the manufacturing operations in making the bit.

I claim:

1. In a device of the class described, a drill rod, 40 a bit having a number of cutting teeth, and a shaped recess formed therein, a shaped shank on the end of the drill rod adapted to fit the bit recess and enable the bit to be revolved when the drill rod is in operation, and means for detachably mounting the bit on the rod shank, comprising a plurality of curved depending lugs formed on the drill rod adapted to bend portions of the top edge of the bit adjacent to the mouth of the bit recess, inwardly about the shank when the 50 drill rod is normally operated.

2. In a device of the class described, a drill rod, a detachable bit having a shaped recess formed therein, a partially concave bottom formed in the bit recess, a shank on the end 55 of the drill rod adapted to fit the bit recess and transmit the torsional strain of the drill rod to the bit, and having a shank length slightly less than the depth of the bit recess, and a plurality of depending recessed lugs formed on the drill rod, adapted when the drill rod is at first operated to bend over portions of the upper edge of the bit, to secure the latter on to the shank, and thereafter to permit the bottom end of the drill rod shank to deliver circumferential impacts on 60 the partially concave bottom of the bit recess.

3. In a device of the class described, a drill rod, a number of upset and depending lugs formed on the drill rod, a bit having a number of cutting teeth thereon and a shaped recess formed therein, a shaped shank on the end of the drill rod adapted to fit into the bit recess and having a 70 number of recesses therein, each of which is opposite to and in proximate relation with one of the depending lugs of the drill rod, said shank

being of slightly less length than the depth of the bit recess for the purpose of permitting the said depending lugs to turn portions of the upper edge of the bit inwardly and hold the latter on the shank when the drill rod is at first operated, and thereafter to permit the bottom of said shank to seat itself in the bottom of the bit recess.

4. In a device of the class described, a drill rod, a detachable bit having a shaped recess formed therein, a shank formed on the drill rod 10 adapted to fit the bit recess, having a number of exteriorly positioned recesses therein, and a length slightly less than the depth of the bit recess, a plurality of depending lugs on the drill rod, each in proximate relation to one of the shank 15 recesses, and adapted when the drill rod is at first operated to bend a portion of the upper edge of the bit inwardly into a shank recess, and thereby provide a means of holding the bit on to the shank of the drill rod.

5. A drill rod adapted to be connected to a bit, a plurality of depending lugs formed thereon, and a shaped rod shank having a plurality of recesses therein, adjacent to said lugs and forming therewith a rod and bit locking means, adapted 25 to bend portions of the top edge of the bit inwardly about the shank when the rod and bit are subjected to impact during the normal operation of the drill rod.

6. In a device of the class described, a drill rod, 30 a detachable bit having a shaped recess formed therein, a concave bottom formed in the bit recess, a shank on the end of the drill rod, adapted to fit the bit recess, and having a shank length slightly less than the depth of the bit recess, 35 and a plurality of depending recessed lugs formed on the drill rod, adapted when the drill rod is operated to bend over portions of the upper edge of the bit, to secure the latter on to the shank, and thereafter permit the bottom end of the 40 shank to seat itself in the concave bottom of the bit recess.

7. A device of the class described, comprising a drill rod having a shaped shank and having lugs overhanging said shank with undercut recesses formed therebetween, and a bit having a conformingly shaped socket for receiving said shank and having an upper wall edge of deformable material, said upper wall edge being so proportioned as to be forced into said recesses and 50 wedgingly secured therein by the impacts incident to the operation of said device.

8. A device of the class described, comprising a drill rod having a shank provided with substantially plane parallel faces and with lugs overhanging certain of said faces and forming undercut recesses therewith, a bit having a conformingly shaped socket for receiving said shank and having an upper deformable socket wall portion 55 adapted to be forcibly deformed to extend into 60 and engage with the surfaces of said undercut recesses.

9. A drilling device comprising a rod member and a bit member having male and female parts, the male part being of substantially constant 65 cross section throughout its contacting extent with said female part, the female part having deformable edge portions and the male part having shoulders provided with undercut recesses for receiving and locking engaging said edge portions of said female part member by deformation of said portions under the impacts occasioned by 70 operation of said device.

PERCILL LIDDICOAT.
